APPROACH CONTROLLED RAILWAY TRACK
CIRCUIT SYSTEM

John Reed Henderson, Wilkinsburg, Pa., assignor
to The Union Switch & Signal Company, Swiss-
vale, Pa., a corporation of Pennsylvania

Application October 23, 1946, Serial No. 705,101

7 Claims. (Cl. 246—220)

1

My invention relates to approach controlled railway track circuit systems, and particularly to the organization of such a system for controlling railway traffic governing devices by traffic approaching such devices.

In railway signaling and traffic controlling systems it is often desirable to provide means whereby traffic in a stretch is enabled to control traffic governing devices in advance of the traffic. For example, it may be desirable to have the approach of a train cause the lighting of normally deenergized signals, or control a normally inactive signal to its proper aspect, or lock a track switch against operation. In establishing such control of traffic governing devices it is customary to use track circuits in which the track rails form the conductors for electric current used to establish the desired control, and it is essential that such track circuit elements be arranged in such manner as to protect against the presence of foreign current in the track rails.

It is an object of my invention to provide novel and improved means whereby the approach of a train is utilized to establish control of traffic governing devices in advance of a train.

Another object of my invention is to provide track circuit means for approach controlling functions in railway signaling systems arranged to provide protection against foreign current in the track circuits.

Another object of my invention is to provide an approach control system utilizing coded track circuit current and requiring a minimum of apparatus to obtain protection against foreign current, overlapping coding contacts, and inductive discharge from the track rails.

Another object of my invention is to provide novel and improved approach controlled means arranged to control traffic governing signals at the opposite ends of a section in response to the approach of a train to that section.

The above-mentioned and other important objects and characteristic features of my invention are obtained by providing a section of track with two track circuits, one comprising a non-coded track circuit in which energy supplied at the entrance end of the section is received at the exit end by a track relay which is effective when released to cause the application of coded track circuit energy to the second track circuit at the exit end of the section for transmission to the entrance end where it operates decoding apparatus at that end. The non-coded track circuit is normally established when the section is vacant, and is controlled by traffic approaching this

2

section so as to establish the coded track circuit under such conditions. The coded track circuit is governed by conditions in advance of the section and the two track circuits are utilized in the control of traffic governing devices at the two ends of the section respectively.

I shall describe one form of apparatus embodying my invention and shall then point out the novel features thereof in claims.

10 The accompanying drawing is a diagrammatic view of a preferred form of apparatus embodying my invention.

Referring to the drawing, the reference characters 1 and 1a designate the track rails of a 15 stretch of railway track in which traffic normally operates in the direction indicated by the arrow, or from left to right as viewed in the drawing. The rails 1 and 1a are divided by means of insulated joints 2 into a plurality of successive adjoining track sections of which two sections AT and T are represented complete in the drawing. The stretch also includes a track switch W positioned in advance of section T with its points facing toward traffic approaching in the normal direction in the stretch. Switch W is provided with the usual circuit controller including a movable contact member 4 controlled by the position of the switch to close a contact 4—5 when and only when the switch is set in its normal position for 20 traffic on the stretch. Contact 4 is operated out of engagement with contact member 5 by switch W when the switch is reversed to permit movement of traffic into a passing track P or whenever the points of the switch are not in alignment for main line traffic movements in the stretch. The reference character NWP designates a switch 25 repeater relay energized whenever switch W is normal, over a circuit extending from one terminal B of a suitable source of current such as a battery not shown, through contact 4—5 operated by switch W, and the winding of relay NWP to the other terminal C of the source of current. The relay NWP therefore constitutes a means controlled by conditions affecting the movement of 30 traffic in the stretch in advance of section T.

The reference characters S with suitably distinguishing prefixes designate signals for controlling the movement of traffic in the stretch. Signal 2S is located at the exit end of section T for governing the movement of traffic over switch W and as shown may comprise a color light signal having two lamps for displaying a green or red aspect, respectively. Signal 2S is controlled by switch W in a manner to be explained hereinafter so as to function as a switch

protection signal. The other signal 1S is located at the entrance end of section T, that is at the junction of sections AT and T, and as shown may also comprise a color light signal having two lamps capable of displaying a green or a yellow aspect, respectively. Signal 1S is also controlled by the position of switch W in a manner which will be explained hereinafter and therefore may be considered a distant signal for signal 2S.

The section AT is provided in the usual manner with a normally energized direct current track circuit comprising a battery 6 connected across the rails of the section at its entrance end, and a track relay ATR connected across the rails at its exit end. Section T also is provided with track circuit apparatus comprising a track battery 7 and a track relay TR at the entrance end of the section; and another track battery 9 and track relay AR at the exit end of the section. Either battery 7 or relay TR is connected across the rails at the entrance end of section T according as relay ATR of the section in the rear is picked up to close its front contact 8 or is released to close contact 8 in its back position. The relay TR has associated therewith decoding means comprising two relays FSA and BSA which operate in a manner that will be pointed out hereinafter. Relays ATR and BSA cooperate in the control of signal 1S in such a manner that one lamp or the other of the signal is lighted whenever relay ATR is released to close its back contact 17, with the selection between lamps Y and G of signal 1S being established by relay BSA according as that relay is released to close its contact 18 in its back position or is picked up to close contact 18 in its front position, respectively. Both lamps of signal 1S are deenergized when relay ATR is picked up and in such a condition the signal is dark.

The relay AR normally is connected across the track rails of section T at its exit end over a stick circuit extending from rail 1 through the winding of relay AR and front contact 10 of that relay to the other rail 1a. Relay AR controls a repeater relay AP over an obvious circuit including front contact 11 of relay AR. Relay AP in turn controls a coding device or code transmitter CT which is set into operation when energized over a circuit extending from terminal B through back contact 12 of relay AP, front contact 13 of relay NWP and the operating element of transmitter CT to terminal C. The transmitter CT has a contact 14 which assumes an intermediate position when the coder is deenergized and which is operable between a first and a second position at a predetermined code rate of, for example, 75 cycles per minute when the coder is energized. When contact 14 of coder CT is in its first position battery 9 is connected across the rails of section T at its exit end, and in the second position of contact 14 the winding of relay AR is connected across the track rails of section T at its exit end in a pick-up circuit. The repeater relay AP and switch repeater relay NWP control signal 2S in such a manner that when both relays are released, lamp R of signal 2S is energized over an obvious circuit including back contacts 15 and 16 of relays AP and NWP respectively; when relay AP is released and relay NWP is picked up lamp G of signal 2S is energized over a circuit including back contact 15 of relay AP and front contact 16 of relay NWP; and whenever relay AP is picked up the circuits for both lamps G and R of signal 2S are interrupted so that this signal is dark.

The apparatus embodying my invention is in its normal condition as represented in the drawing when both sections AT and T are vacant and switch W is in its normal position so that switch repeater relay NWP is energized. In this condition of the apparatus, relay ATR closes its front contact 8 to connect battery 7 across the rails of section T at its entrance end and the rails transmit current from battery 7 to the exit end to energize relay AR over its previously traced stick circuit including its own front contact 10. Relay AP also is energized over front contact 11 of relay AR and as a result coder CT is deenergized so that its contact 14 occupies its intermediate position. All other apparatus of my invention is deenergized so that both signals 1S and 2S are dark.

When a train operating in the normal direction of traffic in the stretch enters section AT, relay 20 ATR is shunted and releases to close its back contact 17 to energize lamp Y of signal 1S over its circuit including back contacts 17 and 18 of relays ATR and BSA respectively. Contact 8 of relay ATR also operates from its front position to 25 disconnect battery 7 from the rails of section T at its entrance end, to its back position where relay TR is connected across the track rails of section T. The disconnection of battery 7 from the rails of section T results in the deenergization 30 of relay AR at the opposite end of the section, so that repeater relay AP releases to close its back contact 15 and energize lamp G of signal 2S. Back contact 12 of relay AP also closes to energize coder CT and set contact 14 into operation. The contact 14 is alternately operated between its 35 first position, in which battery 9 is connected to the track rails of section T at its exit end, and its second position in which the winding of relay AR is connected across the track rails. The periodic 40 connection of battery 9 to the rails of section T results in the supply to the track rails of periodically interrupted or coded current which is transmitted to the entrance end where it intermittently energizes relay TR, but the intermittent connection of relay AR to the track rails over contact 14 of coder CT in its second position has no useful function at this time. The energization of relay TR each time that battery 9 is connected to the track rails, causes relay TR to pick up and close its front contact 20 to energize relay FSA, and the deenergization of relay TR each time 45 battery 9 is disconnected from the track rails by contact 14 causes relay TR to release to close its back contact 20 and energize relay BSA over a circuit extending from terminal B through back contact 20 of relay TR, front contact 21 of relay FSA and the winding of relay BSA to terminal C.

The relay FSA is made slow to release by suitable means, such as a rectifier 22 connected across 50 its terminals, and when relay TR alternately picks up and releases at the predetermined code rate generated by coder CT, the slow release feature of relay FSA maintains its armature picked up during the intervals between code pulses that relay TR is released, so that during these intervals the circuit for relay BSA is completed. Relay BSA also is made slow to release and bridges the intervals that relay TR is picked up. It follows that 55 during operation of relay TR by coded energy applied through contact 14 of coder CT at the exit end of the section, relays FSA and BSA are alternately energized during the energized and deenergized conditions of relay TR respectively, and 70 that when relay BSA picks up under these con-

ditions an indication is provided that relay TR is following code. With relay BSA energized, contact 18 is operated to its front position so that lamp G of signal 1S is energized over its obvious circuit.

It follows from the foregoing that when a train enters section AT, the normally established track circuit for section T that includes battery 7 and relay AR is interrupted so that relay AR releases to cause the signal at the exit end of the section to become lighted; and also to cause coded energy to be supplied at the exit end for operating relay TR at the entrance end. The code operation of relay TR is detected by relay BSA which functions to control signal 1S to its clear indication.

When the train enters section T the coded track circuit energy applied to the section rails through contact 14 of coder CT is shunted away from relay TR and as a result that relay remains in its released position so that both relays FSA and BSA release. This causes lamp Y of signal 1S to be energized over back contact 18 of relay BSA. When the train vacates section AT relay ATR picks up to open its back contact 17 and de-energize signal 1S, while contact 8 of relay ATR operates from its back position to its front position to disconnect relay TR from the rails of section T and to connect battery 7 to the rails, but as long as the train is in the section it shunts energy from battery 7 away from the opposite end of the section.

When the train vacates section T, relay AR is supplied with energy from battery 7 over the previously traced pick-up circuit of the relay, which circuit is established each time contact 14 of coder CT is operated to its second position. Relay AR accordingly picks up over this circuit and closes its front contact 10 to complete its stick circuit which is effective to hold that relay energized during the intervals that contact 14 of coder CT is in its front position to connect battery 9 to the rails and disconnect relay AR from its pick-up circuit. The alternate connection of battery 9 to the rails of the section over contact 14 in its first position, is of no practical effect at this time because relay TR at the entrance end is disconnected from the track rails so that the coded track circuit cannot be established. It is to be noted, however, that when contact 14 is in its first position, a circuit for relay AR is established extending from one terminal of battery 9 through contact 14 of coder CT closed in its first position, front contact 10 of relay AR and the winding of relay AR to the other terminal of battery 9, and that current flows from battery 9 through the relay in the same direction as the direction of current flow in the relay due to battery 7, so that in the first position of contact 14 the relay AR is held up by current from both batteries 7 and 9. The energization of relay AR causes relay AP to pick up and deenergize signal 2S at back contact 15, and coder CT at back contact 12. Coder CT accordingly ceases to operate and positions its contact 14 in its intermediate position and as a result the apparatus is restored to its normal position as represented in the drawing.

In the event that the switch W is not in its normal position, that is, the switch is reversed or the points are out of adjustment, then contact 4-5 operated by the switch will be open with the result that relay NWP is released. If a train should enter section AT under these conditions, relay AR will be released when battery 7 is dis-

connected from the rails of section T by the opening of front contact 8 of relay ATR, and back contact 12 of repeater relay AP will close but since front contact 13 of relay NWP is now open coder 5 CT will not become energized and as a result no coded energy will be applied to the rails of section T. Although relay TR is now connected to the rails at the entrance end of section T, it does not respond to code under the conditions assumed 10 and relay BSA remains released so that lamp Y of signal 1S is lighted over its obvious circuit. Also with relay NWP released, lamp R of signal 2S is caused to become lighted over its circuit including back contact 16 of relay NWP. Under these 15 conditions the fact that switch W is not in its normal position is indicated by the lighted red aspect of signal 2S and the lighted yellow aspect of signal 1S which functions as a distant signal for signal 2S.

20 For a movement into the passing siding P, no change in the apparatus will be effected when the train enters section T but when the train clears section AT relay ATR picks up to open its back contact 17 and deenergize signal 1S, and 25 also to disconnect relay TR from the track rails and connect battery 7 to the rails of section T over front contact 8. When the train vacates section T the apparatus remains in its last established condition with relay AR released and 30 lamp R of signal 2S lighted because under the conditions assumed the apparatus is not self-restoring. That is, when section T becomes vacated energy from battery 7 is no longer shunted away from the exit end of the section but with coder CT deenergized so that its contact 14 is in its intermediate position, and with relay AR released so that its front contact 10 is open to interrupt the stick circuit of that relay, the energy from battery 7 cannot reach relay AR and as a result 35 relay AR remains released. Lamp R of signal 2S accordingly remains lighted to indicate that switch W is not in a position for main line movement, and will remain lighted to indicate this fact until such time as the switch is restored to its normal position. When this happens contact 4-5 operated by the switch closes so that 40 switch repeater relay NWP picks up to close its front contact 13 and complete the energizing circuit for coder CT. Contact 14 of coder CT thereupon is set into operation and when operated to its second position establishes the previously mentioned pick-up circuit for relay AR over which energy from the battery 7 is supplied to that relay. Relay AR accordingly picks up over this 45 intermittently established pick-up circuit and closes its front contact 10 to complete its normal stick circuit. Repeater relay AP is energized over front contact 11 of relay AR and picks up to open its back contact 15 to deenergize signal 2S, and back contact 12 to deenergize coder CT. The 50 operation of coder CT is terminated and contact 14 is positioned in its intermediate position to restore the apparatus to its normal condition as illustrated in the drawing.

55 From the foregoing description it is readily apparent that the apparatus embodying my invention is arranged so that a train approaching section T interrupts the normally established track circuit for that section and causes signal 2S at the exit end of that section to display a lighted aspect determined by conditions in advance of that signal, and if conditions are proper establishes another track circuit for the section which causes the aspect displayed by signal 1S to reflect conditions in advance of the section. Signal 70 75

1S is lighted by the train in section AT but the control of the aspect of the signal is established by means of a track circuit which is completed only if conditions in advance of section T are favorable for main line movements so that signal 1S constitutes an approach signal for the other signal 2S at the exit end of the section. It is to be seen therefore that the track circuit for section T comprising battery 7 and relay AR is controlled by traffic conditions in the rear of section T, while the coded track circuit for section T comprising battery 9 and relay TR is controlled by conditions in advance of section T.

The apparatus embodying my invention is arranged to provide protection against foreign currents in section T. That is, if current from a foreign source is present in the track rails of a nature such as to energize relay AR, the fact that relay AR might be held up by this current even though battery 7 is disconnected from the track rails by the release of relay ATR results in holding repeater relay AP picked up so that both signal 2S and coder CT remain deenergized. Under this condition signal 2S remains dark while signal 1S displays its lighted yellow aspect to provide an indication that the train should be prepared to stop at the next signal. Any failure of the apparatus due to foreign current in the track rails of section T therefore provides a safe failure in that signal 2S will be held dark while signal 1S will be controlled to its most restrictive aspect.

Similarly, apparatus embodying my invention provides protection against both overlapping coding contacts and inductive discharge from the track rails. If contact 14 of coder CT should become deranged so that the contact completes both its front and back points simultaneously instead of alternatively, energy from battery 9 will be provided with a circuit through contact 14 and the winding of relay AR, and as a result relay AR will tend to pick up and energize relay AP so as to deenergize coder CT. Similarly, if conditions in section T are such as to cause energy in the rails to discharge inductively during the period when relay AR is connected to the rails, the energy will flow through relay AR, tending to pick it up and cause relay AP to deenergize coder CT. In the case of either overlapping contacts or inductive discharge from the track rails, the tendency of relay AR to be picked up results in providing protection against unsafe failures of the apparatus because energization of relay AR will result in energization of relay AP, thereby controlling signal 2S to a restrictive (dark) aspect, and in the deenergization of coder CT which results in limiting control of signal 1S to its most restrictive (Y) aspect. The arrangement of the apparatus is thus such that possibility of abnormal operating conditions cannot cause the signals to display aspects less restrictive than warranted under the conditions.

Although I have herein shown and described only one form of approach controlled railway track circuit system embodying my invention, it is to be understood that various changes and modifications may be made therein within the scope of the appended claims without departing from the spirit and scope of my invention.

Having thus described my invention, what I claim is:

1. In combination with a stretch of railroad track divided by insulated joints into two successive adjoining track sections, a first normally

deenergized signal at the junction of said two sections for governing traffic in a given direction in one of said sections, a second normally deenergized signal at the opposite end of said one section for governing traffic in said given direction beyond the opposite end of said one section, a first source of current and a first track relay at said opposite end of said one section, a coding device having a contact operable between a first and a second position and biased to a position intermediate said first and second positions, means governed by conditions affecting the movement of traffic in said stretch beyond the opposite end of said one section, means controlled by said first track relay and by said condition governed means for operating said coding device, means controlled by said contact of said coding device for connecting either said first source or said first track relay in circuit with the rails of said one section at said opposite end according as said contact is in its said first or second position respectively, a stick circuit including a front contact of said first track relay for connecting said first track relay in circuit with the rails of said one section end of said one section, means controlled by said first track relay when released for causing said second signal to display a lighted aspect governed by said condition governed means, a second source of current and a second track relay at the junction end of said one section, means controlled by traffic in the other of said sections for connecting either said second source or said second track relay in circuit with the rails of said one section at said junction end according as said other section is vacant or occupied respectively, decoding means for detecting code operation of said second track relay, and means governed by said traffic controlled means for causing said first signal to display a lighted aspect governed by said decoding means.

2. In combination with a stretch of railroad track including a track switch and two adjoining track sections, said track sections being located in approach to the points of said track switch, a first signal at the junction of said two sections for governing traffic in one of said sections approaching said switch, a second signal at the opposite end of said one section for governing traffic in said one direction over said switch, a first source of current and a first relay at said opposite end of said one section, a coding device having a contact operable between a first and a second position and biased to a position intermediate said first and second positions, means controlled by said first relay and by said track switch for operating said coding device, means controlled by said contact of said coding device for connecting either said first source or said first relay in circuit with the rails of said one section at said opposite end according as said contact is in its said first or second position respectively, a stick circuit including a front contact of said first relay for connecting said first relay in circuit with the rails of said one section at said opposite section end, means governed by said track switch for controlling said second signal, a second source of current and a second relay at the junction end of said one section, means controlled by traffic in the other of said sections for connecting either said second source or said second relay in circuit with the rails of said one section at said junction end according as said other section is vacant or occupied respectively, decoding means for de-

tecting code operation of said second track relay, and means controlled by said decoding means for controlling said first signal.

3. In combination with a stretch of railroad track including an insulated track section, a traffic controlling device at one end of said section, a first source of current and a first relay at the opposite end of said section, a coding device having a contact operable between a first and a second position and biased to a position intermediate said first and second positions, means controlled by conditions affecting the movement of traffic in said stretch beyond said opposite end of said section, means controlled by said first relay and by said condition controlled means for operating said coding device, means controlled by said contact of said coding device for connecting either said first source or said first relay in circuit with the rails of said section at said opposite end according as said contact is in its said first or second position respectively, a stick circuit including a front contact of said first relay for connecting said first relay in circuit with the rails of said section at said opposite section end, a second source of current and a second relay at the one end of said section, means controlled by traffic conditions in said stretch beyond the one end of said section for connecting either said second source or said second relay in circuit with the rails of said one section, decoding means for detecting code operation of said second relay, and means governed by said decoding means for controlling said traffic controlling device.

4. In combination with a stretch of railroad track including an insulated track section, a first traffic controlling device at one end of said section, a second traffic controlling device at the opposite end of said section, a first source of current and a first relay at said opposite end of said section, a coding device having a contact operable between a first and a second position and biased to a position intermediate said first and second positions, means controlled by conditions affecting the movement of traffic in said stretch beyond said opposite end of said section, means controlled by said first relay and by said condition controlled means for operating said coding device, means controlled by said contact of said coding device for connecting either said first source or said first relay in circuit with the rails of said section at said opposite end according as said contact is in its said first or second position respectively, a stick circuit including a front contact of said first relay for connecting said first relay in circuit with the rails of said section at said opposite section end, means governed by said first relay for controlling said second traffic controlling device, a second source of current and a second relay at the one end of said section, means controlled by traffic conditions in said stretch beyond the one end of said section for connecting either said second source or said second relay in circuit with the rails of said one section, decoding means for detecting code operation of said second track relay, and means governed by said decoding means for controlling said first traffic controlling device.

5. In combination with a stretch of railroad track including an insulated track section, a first signal at one end of said section for governing traffic in a given direction in said section, a second signal at the opposite end of said section for governing traffic in said given di-

rection beyond the opposite end of said section, a first source of current and a first track relay at said opposite end of said section, a coding device having a contact operable between a first and a second position and biased to a position intermediate said first and second positions, means governed by track conditions in said stretch beyond the opposite end of said section, means controlled by said first track relay and by said condition governed means for operating said coding device, means controlled by said contact of said coding device for connecting either said first source or said first relay in circuit with the rails of said section at said opposite end according as said contact is in its said first or second position respectively, a stick circuit including a front contact of said first relay for connecting said first relay in circuit with the rails of said section at said opposite section end, means governed by said first track relay and by said condition governed means for controlling said second signal, a second source of current and a second track relay at the one end of said section, means controlled by traffic conditions in said stretch beyond the one end of said section for connecting either said second source or said second track relay in circuit with the rails of said section at said one end according as traffic is not or is approaching said section respectively, decoding means for detecting code operation of said second track relay, and means controlled by said decoding means for controlling said first signal.

6. In combination with a stretch of railroad track including a track switch and an insulated track section, said track section being located in approach to the points of said track switch, a first signal at one end of said section for governing traffic in said section approaching said switch, a second signal at the opposite end of said section for governing traffic in said one direction over said switch, a first source of current and a first track relay at said opposite end of said section, a coding device having a contact operable between a first and a second position and biased to a position intermediate said first and second positions, means governed by the position of said track switch, means controlled by said first track relay and by said switch controlled means for operating said coding device, means controlled by said contact of said coding device for connecting either said first source or said first relay in circuit with the rails of said section at said opposite end according as said contact is in its said first or second position respectively, a stick circuit including a front contact of said first relay for connecting said first relay in circuit with the rails of said section at said opposite section end, means controlled by said first track relay and by said switch controlled means for governing said second signal, a second source of current and a second track relay at the one end of said section, means controlled by traffic beyond the one end of said section, means controlled by said traffic controlled means for connecting either said second source or said second track relay in circuit with the rails of said section at said one end according as traffic is not or is approaching said section respectively, decoding means for detecting code operation of said second track relay, and means controlled by said decoding means for controlling said first signal.

7. In combination with a stretch of railroad track including a track switch and an insulated

11

track section, said track section being located in approach to the points of said track switch, a home signal at the one end of said section for governing traffic over said switch, a distant signal at the opposite end of said section for said home signal, a first source of current and a first track relay at said one end of said section, a coding device having a contact operable between a first and a second position and biased to a position intermediate said first and second positions, 10 means controlled by the position of said switch, means controlled by said first track relay and by said switch controlled means for operating said coding device provided said first track relay is released and said switch is positioned for main line movements in said stretch, means controlled by said contact of said coding device for connecting either said first source or said first relay in circuit with the rails of said section at said one end according as said contact is in its said first or second position respectively, a stick circuit including a front contact of said first relay for connecting said first relay in circuit with the rails of said section at said one section end,

5
